UNITED STATES PATENT OFFICE.

EDWIN NORTON, OF LAKE PLACID, NEW YORK, ASSIGNOR TO THE AUTOMATIC VACUUM CANNING COMPANY, OF NEW YORK, N. Y., A CORPORATION OF ILLINOIS.

CAN-HEADING MACHINE.

968,493.

Specification of Letters Patent. Patented Aug. 23, 1910.

Application filed August 26, 1908. Serial No. 450,263.

To all whom it may concern:

Be it known that I, EDWIN NORTON, a citizen of the United States, residing at Lake Placid, in the county of Essex and State of New York, have invented certain new and useful Improvements in Can-Heading Machines, of which the following is a specification.

This invention relates to an improved machine for applying heads or ends to sheet-metal bodies and has particular reference to a machine for applying heads to sheet-metal cans and commonly termed a header.

One object of the invention is to provide an improved mechanism that will successively feed and force the heads or ends onto the body.

Another object is to provide an improved construction whereby a single mechanism will force one head onto a body while it is feeding other heads for other bodies.

A further object is to provide a construction that will simultaneously feed a plurality of heads or ends in a direct line or at right angles with respect to the open ends of the bodies.

Another object of the invention is to provide an improved mechanism that will enable the heads or ends to be piled or placed in a chute in a horizontal position,—one head or end above another and to separate said heads or ends and force them successively onto the bodies.

A still further object is to provide an improved mechanism that will receive a plurality of heads or ends piled one on top of the other in a horizontal plane and to lower the pile of heads or ends and deliver them successively at the open end of the body and to force said head or end onto the body.

Another object is to provide a screw mechanism that will sustain the heads or ends circumferentially and convey them while thus sustained to the open end of the body.

Other objects and advantages arising as the result of the invention will be herein-after described and made the subject of the appended claims.

The invention is illustrated in the accompanying drawings, in which,

Figure 1 shows a side elevation of the improved machine. Fig. 2, a plan view of the same. Fig. 3, is a central vertical section thereof, and Fig. 4, is a horizontal cross-section of the machine,—the section being

taken on the line 4—4 of Fig. 3. Fig. 5 is a sectional detail of a top and can and shows the relation they have to each other as they are brought together.

In the drawings the numeral, 1, designates a base of any suitable form but in the present instance comprising the sides, 2, and, top, 3. In its present form the base has a bottom flange, 4, by means of which it may be secured in place, and it is also preferably designed with an opening at opposite sides that it may be bolted down on a suitable bed with its side walls, 2, spaced apart in order that a conveyer, 5, having suitable can seats, 6, may travel beneath the top so as to present the can-bodies, 7, successively to receive the heads or ends.

By reference to Fig. 2 it will be clearly seen that the top, 3, is provided with an opening, 8, into which the lower end of a tubular shell, 9, which serves as a chute, is fitted. The shape of this opening and shell depends entirely upon the shape of the head to be applied and while in the present instance the opening and shell are circular it is obvious that the shape of the same may be varied.

On the inner or under side of the head I sustain a plurality of screws, 10, which have position so that their threaded circumferential edges will project slightly across the plane of the opening, 8, in the top of the base. In practice I have found that three screws are sufficient to properly carry out the function for which they are employed but it is to be understood that the number of screws employed is immaterial and may be varied. These screws are sustained on vertical shafts, 11, which extend through and have bearing in the top, and above said top each shaft is provided with a sprocket wheel, 12. A sprocket chain, 13, passes around and engages all the sprockets so that when the chain is driven in a horizontal plane the sprockets and screws will be revolved at opposite sides of the top.

At one side of the top I mount a slotted plate, 14, which carries an idler wheel, 15, at one end and this plate is adjustably secured on the top by means of a bolt, 16. The idler wheel, 15, engages the sprocket chain and serves to take up or adjust the slack in the chain merely by shifting the slotted plate on the top.

In order to drive the chain and thereby

revolve the sprockets and screws, I provide the upper end of one of the vertical shafts with a beveled gear, 17, with which a pinion, 18, on the inner end of a horizontal shaft, 19, meshes. This horizontal shaft 5 may be driven in any suitable manner.

In practice the heads or ends, 20, to be applied to the bodies are first piled or deposited in the tubular shell with their bottom sides facing toward the screws so that 10 the screws will serve as a support for the column of heads or ends.

The heads or ends are circumferentially engaged by the screws which maintain and 15 convey them in a plane parallel with the length of and toward the body.

The bodies are placed on the conveyer, 5, and carried beneath and centered with respect to the screws, and the revolution of 20 the screws causes the heads or ends to be fed toward and forced onto the centered bodies one after another.

It will be noted, by reference to Fig. 5 that the can bodies are provided with a 25 horizontal rim flange, 21, while the top is provided with an annular groove or channel, 22, with a slight depending rim-flange, 23. When the top is forced down onto the body the flange, 21, of the body will fit into the 30 groove or channel, 22, of the top and the body with the top attached is then conveyed to a seaming head or tool which curls or rolls the flanges, 21, and, 23, into a lock seam.

35 It will be seen that while one head or end is being forced onto a body other heads or ends are traveling toward the ends of the screws.

The revolution of the screws effects a continuous feeding of the heads or ends while 40 the bodies are fed intermittently so that they will be centered successively.

It is obvious that the term head or end as used herein means one and the same thing 45 and whenever either expression is employed it is to be construed as covering either the top or bottom of the can as obviously the machine will apply the bottom heads as readily as the top heads.

50 Having thus described my invention what I claim and desire to secure by Letters Patent is,—

1. A body-heading machine comprising an intermittently traveling body support, a 55 head support, and means for continuously conveying heads from the head support toward the intermittently traveling support.

2. A body-heading machine comprising an intermittently traveling body support, a 60 head support, and a plurality of screws operating continuously in a plane between the head support and the traveling support.

3. The combination with a body support, 65 of a plate sustained above the body support and having an opening therein; means for

delivering heads to said opening, and a plurality of screws sustained at the under side of the plate and around said opening whereby to receive the heads passing through the opening.

4. The combination with a body support, 70 of a plate sustained above the body support and having an opening therein, a plurality of vertical shafts extending through the plate and positioned around said opening, 75 screws on said shafts at the under side of the plate, and means on said shafts at the upper side of the plate for revolving said screws.

5. A can-body heading machine comprising 80 a traveling support having means to sustain can bodies, of means for holding the heads; head-feeding and applying means spaced from the traveling support and in close proximity to the end of the cans to 85 be headed, and means for operating the feeding and applying means for conveying a plurality of heads simultaneously from the holding means toward the end of the body to be headed and forcing the foremost of 90 said plurality of traveling heads onto the body.

6. A heading machine comprising a can-body support to sustain the bodies from 95 their ends, of means for holding the heads; means for simultaneously conveying a plurality of heads; means for moving the can-body support to present the bodies successively beneath the feeding device and means for operating the head feeding device continuously in one direction to force the heads onto the bodies.

7. A heading machine comprising a can-body support to sustain the bodies in a vertical position, of means for holding the 105 heads; a plurality of screws disposed about a common center and depending below the head holding means; means for intermittently moving the body support to present the bodies successively beneath the screws 110 and means for turning the screws to feed and force a head onto the end of the body.

8. A heading machine comprising an intermittently moving can-body support to sustain the bodies with the end to be headed uppermost, of a plate sustained over the support and having an opening; vertical screws disposed about said opening and sustained from the plate; means on top of the plate for revolving the screws and forcing the heads 120 onto the body below the same.

9. The combination with a traveling support having means to sustain can-bodies on their ends, of a plate over the traveling support and having an opening therein; a chute 125 registering with the opening in said plate; a plurality of vertical screws disposed about said opening and projecting slightly therein and serving to sustain a pile of can-heads placed in the chute and means for revolving 130

said screws and lowering the heads and forcing the lowermost head onto a can body.

10. The combination with a traveling support provided with a plurality of can-body seats to sustain the bodies on their ends, of a plate above the traveling support; a plurality of screws depending over said support and disposed about a common center; means for delivering can heads to the 10 screws and means for revolving the screws to force the heads downward onto the upper end of the can bodies.

11. The combination with a traveling support provided with a plurality of can-body seats to sustain bodies on their ends, of a plate above the traveling support; a 15

plurality of vertical shafts depending from said plate and each carrying a vertical screw at the under side of the plate,—said shafts and screws being disposed about a common center; a sprocket on each of said vertical shafts; a chain embracing said sprockets, and means for driving the chain whereby to revolve the screws and force the heads onto the bodies presented by the traveling support.

In testimony whereof I affix my signature in presence of two witnesses.

EDWIN NORTON.
